BELL TREE MUSICAL INSTRUMENT

Grover C. Jenkins, Decatur, Ill., assignor to
G. C. Jenkins Co., Decatur, Ill.

Application June 22, 1954, Serial No. 31,106

Term of patent 3½ years

(Cl. D56—1)

I claim:

The ornamental design for a bell tree musical instrument, as shown.
